DESIGN FOR AN AUTOMOBILE ORNAMENT

George B. Warner, Eatontown, N. J., assignor to the Commissioner of Welfare of the City of New York, New York, N. Y.

Application December 19, 1946, Serial No. 135,626

Term of patent 3½ years

(Cl. D14—18)

To all whom it may concern:

Be it known that I, George B. Warner, a citizen of the United States, residing at Eatontown, in the county of Monmouth and State of New Jersey, have invented a new, original, and ornamental Design for an automobile ornament, of which the following is a specification, reference being had to the accompanying drawing, forming a part thereof.

I claim:

The ornamental design for an automobile ornament, as shown.

GEORGE B. WARNER.
